UNITED STATES PATENT OFFICE.

DAVID B. ASHMAN, OF BALTIMORE, MARYLAND.

WORK GUIDE-BUTTON FOR BUTTONHOLE-SEWING MACHINES.

No. 832,831.

Specification of Letters Patent.

Patented Oct. 9, 1906.

Application filed January 27, 1906. Serial No. 298,105.

To all whom it may concern:

Be it known that I, DAVID B. ASHMAN, a citizen of the United States, residing at Baltimore, in the State of Maryland, have 5 invented certain new and useful Improvements in Work Guide-Buttons for Button-hole-Sewing Machines, of which the following is a specification.

My invention relates to an improved work 10 guide-button for buttonhole-sewing machines, and is particularly designed for use on what is known to the trade as the "Singer" buttonhole-sewing machine.

Heretofore the guide-buttons employed in 15 the machines referred to have been made of a single piece of metal and although only a slight portion of the button is subjected to wear the whole button must be discarded when that one part is sufficiently worn to 20 interfere with the character of the work. This entire discarding of the button is objectionable, not only because good and unworn parts are thrown away, but also because those unworn parts contain features of 25 constructions that meet the wants of the particular manufacturer using the buttons. These special features vary according to the ideas of the manufacturer and they relate to the particular formation of the slot through 30 which the needle passes and the position of the gimp-hole with respect thereto. It is desirable, therefore, as the wear on these parts is almost nothing that they be retained and only the worn parts replaced.

35 By my invention I am able to provide a button that will fulfil these requirements and enable the worn parts to be removed without the necessity of discarding the entire button.

40 As the disclosure of the invention is directed to those skilled in the art to which the invention relates, it is deemed sufficient to illustrate the button only.

The accompanying drawings illustrate the 45 invention, in which—

Figure 1 shows a top plan view of the improved button, Fig. 2 an edge view of the same, Fig. 3 a bottom plan view of the same. Fig. 4 is a perspective view of the permanent 50 button portion, Fig. 5 a similar view of the removable portion of the button, and Fig. 6 shows a sectional elevation through the two portions of the button.

Referring to the drawings by numerals, 55 1 designates the base of the permanent button portion, which is provided with a central

hollow stud 2, closed at its outer end, and which closed end is provided with the usual slot 3 for the passage of the needle and a gimp hole or perforation 4 adjacent said 60 needle-slot. These parts are preferably formed in one integral piece; but this is immaterial so far as the present invention is concerned.

A removable sleeve or collar 5 surrounds 65 the stud 2, and in the present instance the sleeve is attached to a plate 6, from which the sleeve 5 projects and by means of which said sleeve may be secured to the base 1 of the permanent button portion. The outer 70 end of the sleeve is provided with a circular flange 7, which has position in a plane below the closed end of the stud 2. The sleeve may be fitted over the stud and held thereon by screws passing through the plate 6 into 75 the base-plate 1.

It will be understood by those skilled in the art that the cloth-holding clamp of the sewing-machine is guided in its movement around the button by frictional contact with 80 the sleeve and when the sleeve becomes worn it alone may be removed from the stud and replaced by a new sleeve and the specially-constructed and permanent stud is retained. Another advantage gained by 85 means of the movable sleeve or collar 5 is that as the wear on the sleeve takes place at one side only—to wit, that side against which the work-holder is pressed—when said side becomes worn the sleeve may be slightly 90 rotated on the stud and an unworn side thus be presented to the work-holder. Thus by shifting the sleeve or the stud the life of the button may be prolonged.

Having thus described my invention, what 95 I claim as new, and desire to secure by Letters Patent, is—

1. A guide-button for sewing-machines having a base-plate for rigid attachment to the machine with a permanent stud projecting from said base-plate, and a work-holder 100 guide device around the stud and removably attached with respect thereto whereby the guide device when worn may be removed independently of the stud.

2. A guide-button for sewing-machines having a base-plate; a stud projecting from the base-plate and having perforations in its end, said stud having a uniform cross-sectional dimension from the base-plate to its 105 upper end and a removable sleeve fitting over the stud and secured to the base-plate.

3. A guide-button for sewing-machines having a base-plate a stud projecting from said base-plate and having perforations in its end, a sleeve surrounding the stud and having a plate at one end by which it may be secured to the base-plate and also having a flange at its opposite end adjacent the perforated end of the stud.

4. A guide-button for sewing-machines having a stud with a perforated end, a removable sleeve around the stud for guiding

the work-holder and means whereby when one portion of the sleeve becomes worn it may be partly rotated on the stud to present an unworn surface to the work-holder.

In testimony whereof I affix my signature in presence of two witnesses.

DAVID B. ASHMAN.
